UNITED STATES PATENT OFFICE.

WILLIAM C. BURRY, OF ALLEGHENY CITY, PENNSYLVANIA.

EGG-BEATER.

SPECIFICATION forming part of Letters Patent No. 328,457, dated October 20, 1885.

Application filed April 27, 1885. Serial No. 163,685. (No model.)

To all whom it may concern:

Be it known that I, WILLIAM C. BURRY, of Allegheny City, in the county of Allegheny and State of Pennsylvania, have invented a new and useful Improvement in Egg-Beating Machines; and I do hereby declare the following to be a full, clear, and exact description of the invention, such as will enable others skilled in the art to which it pertains to make and use it, reference being had to the accompanying drawings, which form part of this specification.

My invention relates to an improvement in egg-beating machines, the object being to provide an egg-beating machine of simple and durable construction and of small cost; and to that end my invention consists in a beater constructed substantially as hereinafter described, and specifically pointed out in the claim.

In the accompanying drawings, Figure 1 is a side elevation of my improved egg-beating machine constructed in accordance with my invention, the pail being shown in section the better to illustrate the beater. Fig. 2 is a plan view of the same. Fig. 3 is an enlarged perspective view of the clamping-jaws on one end of the vibrating arm.

To put my invention into practice I provide a frame, A, of suitable size, form, and construction, and capable of maintaining the moving parts without vibration. At the top of this frame A, I place a large belt-wheel, b, sustained on a shaft, c, with suitable bearings, d e. To one end of the shaft c, I place a crank, f, for operating the machine. Directly under the large pulley b, I place one, y, of less diameter. To the right of this and on the same shaft g is a fly-wheel, h, to assist the working of the machine. On the other end of the shaft is a crank, i, to which I attach the vibrating arm J, constructed in two sections, k l, pivoted at m, near the end, which forms the jaws n o, used to hold the beater O. Near the other

end is a clamping-screw, p, provided with a thumb-piece, q, which serves to hold the jaws n o together. Near the middle of the lower section, l, of the vibrating arm J, I also pivot it to a horizontal piece, r, resting on a stand, s. Said piece r is also resting on pivots t, which allows it to be moved vertically. The beater O I construct with a series of bent wires, u, provided with a handle, v, for fastening to the vibrating arm J. The pail or vessel w is provided with an extension, x, at the top, bent inwardly, which prevents the fluid when violently agitated from splashing out.

The operation is as follows: The vessel w, holding the eggs to be beaten, is placed under the beater O, which is adjusted to the proper angle, so as to come near the bottom of the vessel w. By turning the crank f causes the pulley b to rotate. A belt, z, transmits the power to a smaller pulley, y, which revolves the crank i, carrying the vibrating arm J, giving the beater O a circular vibratory motion. The arm J is allowed to move in a circle in consequence of being pivoted horizontally and vertically, thereby imparting to the beater O the peculiar motion used in beating eggs.

Having thus described my invention, what I claim, and desire to secure by Letters Patent, is—

In an egg-beating machine, the vibrating arm J in two sections, k l, provided at one end with clamping-jaws n o for holding the beater O, said arm J pivoted horizontally and vertically to the cross-piece r, supported by a stand, s, and a crank, i, for imparting motion to the same, and suitable driving-wheels, b y, for operating the crank i, as and for the purpose herein specified.

WILLIAM C. BURRY.
